ATTORNEYS

UNITED STATES PATENT OFFICE.

ANTHONY FRANCIS McDONNELL, OF DUNMORE, PENNSYLVANIA, ASSIGNOR OF ONE-
THIRD TO WILLIAM ALOYSIUS QUINN, OF SCRANTON, PENNSYLVANIA.

CLOSURE FOR CONTAINERS.

Application filed April 17, 1928. Serial No. 270,749.

My invention relates more particularly to that class of closures for bottles, jars, and other rigid containers in which the bottle neck, for example, is enlarged by a peripheral bead or otherwise around the mouth of the bottle, and the cap, for example, that known as the "Crown" cap, which is provided with a cork or other lining in its crown to seal the mouth of the bottle, is crimped or compressed to form a contracted rim bound tightly around the neck of the bottle, and secured against displacement thereon by the enlargement around the mouth of the bottle.

The Crown cap has heretofore generally been removed when desired by a special tool for the purpose which often distorts the cap in removal, so that it cannot be used again even for temporarily closing the container, as when only part of the contents is to be used at a time.

The primary object of my invention is to provide a neck for bottles, jars and similar containers so formed that the cap, when crimped or compressed thereon, as by means of the ordinary crimping machines in common use, will be securely held in place against leakage and displacement, and yet can be easily removed by hand without the use of any tool, and after removal can be easily replaced on the neck for temporarily closing the container when only part of its contents have been used.

To this and other ends, my invention consists broadly of a container, for example, a bottle, having a neck formed with peripherally and upwardly inclined beads or shoulders to engage inward projections, or some of the corrugations, if a Crown cap, on the inside of the rim thereof and lift the cap off the neck as the cap is turned, and with upwardly and outwardly inclined parts, by which the rim of the cap, when crimped or contracted around the neck, is locked in place, and which, when the cap is turned by hand, will act to expand the rim and ease the lifting of the cap off the neck.

My invention also consists more specifically, in forming the peripherally and upwardly inclined shoulders on the upper sides of beads raised around the neck of the bottle, the undersides of which, when the several beads overlap, serve with the outwardly inclined parts of the neck, to engage the inward cap projections and lock the cap in place.

The inclined shoulders on the neck may also be formed of inclined grooves in the neck.

The broad invention and the specific form thereof above briefly stated are not claimed herein but are described and claimed in a separate application for patent filed by me April 17, 1928, Serial No. 270,750.

The present application is specifically for another specific form of my broad invention described but not claimed in my said other application, and consists in forming the peripherally and upwardly inclined cap-lifting shoulders on the neck in pairs converging downwardly and the parts of the neck between the shoulders flaring or inclined upwardly and outwardly. The downwardly converging shoulders will engage the inward projections of the cap, crimped or contracted thereon, when turned in either direction and lift the cap off the neck, and the upwardly and outwardly inclined parts of the neck between the shoulders will serve to lock the cap in place when crimped or contracted thereon and to spread the rim of the cap and ease its lifting and removal when so turned in either direction.

In order that this specific form of my invention may be fully understood, I shall first describe in detail the mode in which I at present prefer to carry the invention into practice, and then particularly point out the invention in the claims.

Reference is to be had to the accompanying drawings forming part of this application in which like parts are designated by the same numbers in all the figures.

Figure 1 is a sectional side view of a bottle neck with Crown cap embodying my invention.

Figure 2 is a cross-sectional view of the same on the line 2-2, Figure 1.

Figure 3 is a side view of the said bottle neck.

In the drawings, 5 designates the Crown cap here shown to illustrate one use of my invention, 6 the corrugated rim thereof which is contracted, usually by crimping, around the neck of the bottle, and 7 the usual internal corrugations on the inside of the rim.

8 designates the bottle neck, which I form with peripherally and upwardly inclined shoulders 9, arranged in pairs converging downwardly from the mouth 10 of the bottle,

so that when the corrugated rim 6 of the cap is crimped on the neck 8, some of the corrugated projections 7, will enter between the converging shoulders, and when the cap 5 is turned by hand in either direction, said projections 7 will engage and ride peripherally and upwardly on the corresponding shoulders 9, and lift the cap off the neck.

The parts 11 of the neck between the shoulders 9 are flared or inclined upwardly and outwardly toward the mouth 10 of the bottle, so that when the cap rim is crimped or contracted thereon, the cap will be locked securely on the neck, and when the cap is 10 turned by hand in either direction, and lifted off the neck by the shoulders 9, the rim of the cap will be evenly and gradually spread by the upwardly and outwardly inclined parts 11, the removal of the cap thus facilitated, and the destructive distortion thereof 15 caused by the ordinary tool, prevented. As a result the cap being flexible, can be easily slipped over the cap-expanding and securing parts 11 and replaced temporarily to cover 20 the remaining contents of the bottle when only a part thereof has been used.

I prefer to make the depth of the converging cap-lifting shoulders 9 greater at the bottom where the initial and greatest resistance to removal of the cap is met and slightly diminishing to the top to make a better finish 25 at the mouth of the bottle.

I also may slightly depress transversely the outer parts 12 of the neck between the

pairs of shoulders at the bottom, the better 35 to accommodate the part of the rim contracted against the same.

It is evident that this improved form of container neck may be used with other caps than the Crown cap, which have a rim 40 adapted to be contracted below the mouth of the bottle and interior projections on the rim which will enter between and engage the downwardly converging shoulders 9.

It is also evident that other changes may 45 be made in the practice of my invention without departing from the boundaries thereof as defined by the following claims.

I claim as my invention:

1. A bottle or other container having its 50 neck formed with shoulders inclined peripherally and upwardly toward the mouth and arranged in pairs converging downwardly so as to be engaged by intervening inward projections on the rim of the cap 55 and lift the cap when turned in either direction, and with parts intervening the shoulders inclined outwardly and upwardly toward the mouth to engage and lock the cap rim contracted around the neck and to expand the rim when the cap is lifted by the inclined shoulders.

2. A bottle or other container in accord 60 with claim 1, in which the converging shoulders decrease in depth toward the mouth. 65

In testimony whereof I affix my signature.

ANTHONY FRANCIS McDONNELL.
